UNITED STATES PATENT OFFICE.

EMIL HAAG, OF HETTINGER, NORTH DAKOTA.

HOISTING DEVICE AND WIRE-STRETCHER.

1,256,686.

Specification of Letters Patent. Patented Feb. 19, 1918.

Application filed June 16, 1913. Serial No. 774,018.

To all whom it may concern:

Be it known that I, EMIL HAAG, a citizen of the United States, residing at Hettinger, in the county of Adams and State of North Dakota, have invented certain new and useful Improvements in Hoisting Devices and Wire-Stretchers; and I do hereby declare the following to be a full, clear, and exact description of the invention, such as will 5 enable others skilled in the art to which it appertains to make and use the same.

This invention relates to new and useful improvements in block and tackle equipment and as its principal object contemplates 15 the provision of a block and tackle which may be effectively employed in stretching fence wires, hoisting material, producing the desired tension on cables during the operation of splicing their ends or for the 20 performance of any other analogous operation.

A further object of this invention is to construct the device with such regard to proportion, number and arrangement of parts that it may be cheaply manufactured, will be 25 durable and efficient in its action and may be readily employed in any of the operations above set forth.

The above and additional objects are accomplished by such means as are illustrated 30 in the accompanying drawings, described in the following specification and then more particularly pointed out in the claim which is appended hereto and forms a part of this application.

With reference to the drawings, wherein 35 I have illustrated the preferred embodiment of my invention as it is reduced to practice and throughout the several views of which similar reference numerals designate corresponding parts:

Figure 1 is the front elevation.

Fig. 2 is the side elevation.

Proceeding now to the description of the drawings the numeral 1 designates as an 40 entirely a multiple pulley block equipped with the usual attaching hook 2. A cable 3 plays through the pulley block 1 and is designed to be wound upon a winding spool 4 which is journaled in the side members 5 and 6 of a substantially rectangular spool 45 frame, the one end of which extends laterally to the members 5 and 6 and is designated by the numeral 7, the other of which consists of two angular frame members 8 and 9 which are formed integrally with the members 5 and 6. The members 8 and 9 are bent at their 50 extreme terminals to produce a pair of apertured ears 10 and 11 which extend in parallel relation to each other and are designed to receive between their adjacent faces an idler 60 pulley 12 which is rotatably mounted on a pin 13. The pin 13 extends beyond the outer faces of the members 10 and 11 to receive the apertured terminals of a U-shaped clevis 14 employed in attaching one terminal of the 65 cable 3 to the frame. The winding spool 4 is equipped with a pair of terminal spacing disks 15 and 16, which are provided for the obvious purpose of preventing the chafing of the cable 3 against the side frame members 70 5 and 6 during the winding and unwinding operations. Formed integrally with the spool 4 and disposed exteriorly of the side frame member 6 is a handle 17 of the usual 75 type. The transverse frame member 7 carries a pair of swivel eyes 18 to which are attached the terminals of a connecting chain 19. An attaching hook 20 is connected to the chain 19 and at the middle point thereof.

From the foregoing it will be apparent 80 that in operation the terminal of the wire which the operator desires to stretch may be attached to the hook 2 and the hook 20 may be secured to a fence post or any other adjacent structure. By rotating the handle 85 17, the operator may readily wind the cable 3 on the spool 4 thus shortening the distance between the block 1 and the idler pulley 12 with a resultant tightening of the wire 90 which is being stretched. In order to permit 95 the operator to release the handle 17 without permitting the spool 4 to unwind there has been provided a locking arm 21 which consists essentially in an elongated metal bar or rod pivotally attached as at 22 to the central point of the transverse frame member 7. The free end of the member 21 arranged to extend a slight distance beyond the side frame member 6 and is designed to be limited in its swinging movement by the side 100 frame member 6. It will be apparent, therefore, that by swinging the arm 21 into the position indicated in Fig. 2 the operator may prevent the negative rotation of the handle 17 through a greater distance than 105 through one revolution. It will also be apparent from the foregoing that by swinging No. 21 into a position of lateral relation to the transverse frame member 7, the handle 17 may be allowed to rotate in the desired 110 manner when the operator is winding or unwinding the cable 3.

It is to be noted that the number of pulleys in the block 1 may be varied as occasion may demand.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

What is claimed is:

A wire stretcher designed for stretching single wires and including an open oblong frame arranged horizontally to enable it to operate between the wires and having the forward portions of its sides converging and arranged in spaced relation, a pin connecting the front ends of the sides of the

frame, a clevis connected with the pin, a pulley mounted on the pin, a rod journaled on and extending across the frame and having one end bent to form a crank handle, a pulley block, a cable reeved over the pulley and through the pulley block and connected to the rod, and a straight locking bar pivoted at one end to the back of the frame at the inner face thereof and arranged to be swung by hand outwardly and upwardly against the underside of one side of the frame and being of a length to extend into the path of rotation of the crank handle and forming a lock for the same, said locking bar extending along the back of the frame when in engagement with the crank handle and adapted to swing downward out of the way by gravity.

In testimony whereof I affix my signature in presence of two witnesses.

EMIL HAAG.
